(57) **CLAIM**

I claim the ornamental design for the cigarette making machine, as shown and described.

DESCRIPTION

FIG. 1 is a front, left side, perspective view of a cigarette making machine in accordance with the new design;

FIG. 2 is a right side elevational view of the cigarette making machine of FIG. 1;

FIG. 3 is a rear side elevational view of the cigarette making machine of FIGS. 1 and 2; and,

FIG. 4 is a bottom plan view of the cigarette making machine of FIGS. 1-3.

The broken lines immediately adjacent the shaded areas represent the bounds of the claim and all other broken lines are for illustrative purposes only. None of the broken lines form a part of the claimed design.
